UNITED STATES PATENT OFFICE.

SAMUEL E. HASKIN, OF AVOCA, NEW YORK.

METHOD OF VULCANIZING WOOD.

SPECIFICATION forming part of Letters Patent No. 399,196, dated March 5, 1889.

Application filed December 5, 1887. Renewed September 29, 1888. Serial No. 286,754. (No specimens.)

To all whom it may concern:
Be it known that I, SAMUEL E. HASKIN, of Avoca, in the county of Steuben and State of New York, have invented certain new and useful Improvements in the Method of Vulcanizing Wood; and I do hereby declare the following to be a full, clear, and exact description of the invention, such as will enable others skilled in the art to which it pertains to make and use the same.

My invention relates to an improved method of vulcanizing wood; and it consists in the steps hereinafter described and claimed.

Heretofore in vulcanizing wood cold air was forced into the vulcanizing-chamber, or so-called "wood-cylinder," until the desired air-pressure was attained, the air in the wood-cylinder being heated by coils of steam-pipe lining such cylinder. There were several serious objections to such method. If the wood-cylinder was of practical size—for instance, of about eight feet in diameter and from fifty to sixty feet long—a mile or more in length of steam-pipe was required with which to construct the heating-coils. Such heating-coils were not only very expensive, but it was almost impossible to prevent the leakage of steam from some portion of such an extensive coil, and any leakage of steam in the wood-cylinder was a serious objection, in that the steam discolored and injured the wood being treated in the cylinder. It will be readily understood that an expensive boiler-plant was required to furnish steam to supply a coil of such large dimensions, and that a high pressure of steam was required to raise and maintain the temperature—say from 250° to 400° or 500° Fahrenheit, according to the variety and dimensions of the wood being treated and according to the purposes for which such wood was intended. These, in brief, are some of the difficulties encountered in vulcanizing wood with the method heretofore employed.

My improved method will be more readily understood by referring to the accompanying drawings.

Figure 1 is a side elevation partly in section, the central portion of the wood-cylinder being broken away to reduce the size of the drawing. Fig. 2 is an elevation in transverse section through the wood-cylinder.

A represents the so-called "wood-cylinder," the same inclosing the vulcanizing-chamber in which the wood is treated. This cylinder 55 may be of any desired size—say about eight feet (more or less) in diameter, and preferably from eighty to a hundred feet in length. The cylinder is made, preferably, of heavy steel plate riveted together, after the manner of 60 constructing steam-boilers, and at least one of the cylinder-heads A' must be removable to allow the passage of cars laden with lumber to and from the cylinder. Inside the cylinder are tracks a for the cars a' to travel 65 on. A series of cars are employed and the lumber is piled loosely thereon, and the cars are run into the cylinder, after which the removable head is secured, hermetically closing the cylinder. 70

B is the air-compressor; C, a heater; D, a storage-tank, and E a furnace. The branch F of the induction-pipe of the compressor connects with the rear end of cylinder A, while the other branch, F', opens into the air, 75 these two branch pipes being provided, respectively, with stop-valves f and f'. The eduction-pipe of the compressor has a branch pipe, G, leading direct to tank D, this pipe passing in at the top of the tank and discharging near the bottom of the tank, substantially as shown, this pipe being provided with valve g. The other branch, G', of the eduction-pipe leads through heater C, this pipe being provided with valves g' and g'', arranged on either side of the heater. 80

Pipe G' preferably joins G before reaching the tank D. By manipulating the valves of the eduction-pipe the air from the compressor may be discharged directly into tank D, or 90 may be made to pass through heater C on its way to the tank. Heater C is provided with induction and eduction pipes c and c' for the passage of steam to and from the heater, exhaust-steam being usually employed for the 95 purpose, thus utilizing the exhaust of the engine that drives the compressor and other machinery, which would otherwise be wasted. Tank D is provided with safety-valve D', with glass water-gage d, and with drain-pipe and 100 cock d'. The air-discharge pipe connects at or near the top of the tank, for instance, as shown. This pipe has a branch, H, leading direct to cylinder A, and connects, prefera-

bly, near the front end of the latter, this pipe being provided with valve h . The other branch, H' , leads to the furnace E, preferably joining branch H, pipe H' being provided on either side of the furnace with valves, respectively, h' and h^2 , and this pipe being made into a suitable heating-coil where it passes through the furnace. By manipulating these valves the air from tank D may be passed directly to cylinder A, or may be passed through the coils in the furnace E on its way to the cylinder. Pipe I leads from the rear end of the cylinder and connects with pipe G, pipe I having a valve, i , and having connected in line thereof a fan-blower, K. Cylinder A is provided with heat and pressure gages and with safety-valve L, of large capacity. Cylinder A, the heater, tank, and pipes, are all jacketed so as to radiate as little heat as possible. Cylinder A having been charged and closed as aforesaid, valves f , g , h , and i are closed and valves f' , g' , g^2 , h' , and h^2 are opened and the compressor is set in motion. The air, in passing through heater C, becomes moderately heated, and in passing through tank D, owing to the arrangement of pipes as aforesaid, much of the moisture of the air is precipitated, and the water that accumulates is drawn off from the tank from time to time through pipe d' to keep the mouth of pipe G free, the water-gage of course indicating the depth of water in the tank. The air passing from tank D is superheated in passing through the coils in the furnace and in such superheated condition is discharged into the cylinder A. The compressor is kept in operation until the desired air-pressure is had in cylinder A. The air introduced into the cylinder during the earlier stages of the process will of course be chilled and greatly reduced in temperature by contact with the cylinder, and more especially by contact with such large quantity of lumber. In this cylinder, so to speak, the pressure should always be kept in advance of the temperature—that is to say, the pressure should always be such as to prevent the possibility of the sap of the wood boiling or vaporizing under whatever degree of heat is being employed; otherwise the boiling of the sap would injure the fiber of the wood, and the sap, being vaporized, would escape from the wood, thus defeating the object in view—to wit, to retain and vulcanize all of the sap in the wood. With a compressor of the ample capacity desirable, during the first stage of the process the pressure is likely to be kept considerably in advance of the temperature, and under such conditions valve f' may be partially closed and valve f partially opened to give a circulation of air through cylinder A, and cause at least a portion of this air to again pass through the heating-coils of the furnace. When the compressed air has reached such high temperature that no additional heat will be imparted in the heater during such circulation of the air,

valve g is opened and valves g' and g^2 are closed, thus cutting out the heater. This would not likely occur so long as cold air is being forced in by the compressor. When the air-pressure in cylinder A has reached the maximum desired, valve f is closed, and valve g had better be closed also, and valve i opened instead, and the blower K used to give the necessary circulation to keep the compressed air at the required temperature by passing it through the heating-coils of the furnace, for the reason that the fan-blower is likely to work better than the compressor with the air at a high temperature. Meantime, as there are preferably several storage-tanks D, only one of which is shown, and usually only one at a time being used for precipitating the moisture of the compressed air, the compressor may be used to advantage in forcing air into such auxiliary storage-tanks, the pressure in which latter should reach something more than the maximum pressure wanted in cylinder A, so that if it is desired to increase the pressure in cylinder A at any time—for instance, during the latter stage of the process—it may be done by admitting air from one of these reserved tanks rather than resorting direct to the compressor. When such auxiliary storage-tanks are provided and kept charged with compressed air, the air from these tanks may be used to advantage in, first, filling cylinder A, and much time may be saved by such practice over filling the cylinder entirely from the compressor. Such auxiliary tanks are all connected in the pipe system substantially like the tank shown, so that either of them may be used in connection with heater C and furnace E.

I will remark that it will be better practice to provide a series of small furnaces E with the heating-coils passing through the series, rather than rely on one large furnace, for the reason that one or more such furnaces may be used at a time, as may be required, and the temperature of the air passing through the heating-coils can be better regulated than with one large furnace. After the wood has been treated from four hours to twenty-four hours, and subjected meantime to a temperature of from 225° to 400° or 500° Fahrenheit, according to the variety and dimensions of the wood and the uses for which the wood is intended, cylinder A and contents are cooled down in the following manner: With valves f , g' , g^2 , h' , h^2 , and i closed, and with valves f' , g , and h open, the compressor is set in motion to force cold air into cylinder A, such air of course passing by the heater and furnace, but passing through tank D for the purpose aforesaid. The safety-valve L is set to maintain the maximum pressure had during the vulcanizing process, and the surplus air had by operating the compressor is blown off through valve L. As the temperature in cylinder A becomes reduced, safety-valve L may from time to time be changed to reduce the pressure, care being had not to reduce the pres-

ure below the boiling-point, so to speak. The operator, having memorized the table giving the degrees of heat necessary to reach the boiling-point under different pressures, and 5 with the pyrometer and pressure-gage of cylinder A before him, will have no difficulty in cooling down the wood-cylinder, keeping always such a pressure therein as to preclude the possibility of the sap boiling in the wood, 10 and when a temperature somewhat below 212° Fahrenheit is reached the air-pressure may be dispensed with and the wood-cylinder opened and its contents discharged.

The method herein described marks a radial 15 cal advance in the art of vulcanizing wood. In the matter of initial cost the apparatus for carrying out my improved method is much less expensive than the necessary apparatus for carrying out the old method. For instance, by dispensing with the heating-coils 20 in the wood-cylinder from two to three thousand dollars are saved and the wood-cylinder is made to contain several thousand feet more of lumber. The heating-furnace 25 and coils connected therewith are much less expensive to construct and operate than the necessary boiler-plant used with the old method. Considerable saving is effected by using the exhaust-steam of the engine that 30 drives the compressor in heater C, as aforesaid; also precipitating the moisture of the air in tank D is found to be of great advantage, in this that the quality of the vulcanized product is much improved by such practice. In the absence of heating-coils in cylin- 35

der A the latter is cooled down in perhaps a third of the time formerly required.

What I claim is—

1. The method herein described of vulcanizing wood, consisting, essentially, in introducing heated air into the vulcanizing-chamber and under such pressure as will prevent the evaporation of the sap of the wood being treated, substantially as set forth. 40

2. The method herein described of vulcanizing wood, consisting, essentially, of introducing heated air into the vulcanizing-chamber under such pressure as will prevent the evaporation of the sap of the wood being treated, more or less of the moisture of such 50 compressed air having been precipitated before the air is discharged into the wood-cylinder, substantially as set forth.

3. The method herein described of vulcanizing wood, consisting, first, in compressing air and heating the same; second, precipitating the moisture of the air; third, superheating the air and introducing such dry superheated air into the vulcanizing-chamber 55 under such pressure as will prevent the evaporation of the sap of the wood being treated, substantially as set forth.

In testimony whereof I sign this specification, in the presence of two witnesses, this 14th day of November, 1887.

SAMUEL E. HASKIN.
